CLAIM

I claim the ornamental design for the interior of a shot glass, as shown and described.

DESCRIPTION

FIG. 1 is a perspective view of the interior of a shot glass showing my new design;

FIG. 2 is a side elevation view thereof wherein the claimed elements appear the same from all sides;

FIG. 3 is a top plan view thereof; and,

FIG. 4 is a bottom plan view thereof.

The broken lines in the drawings are for illustrative purposes only and do not form part of my claim. The circular broken line with the shorter segments in FIGS. 1, 3, and 4 is a boundary between the claimed design inside it and environmental structure.
